MOLLETON ROLL FOR LITHOGRAPHIC PRESSES

Clarence Lloyd Claff and Carl A. Moeller, Randolph, Mass., assignors to M. B. Claff & Sons, Inc., Randolph, Mass., a corporation of Massachusetts

Application July 3, 1953, Serial No. 366,040

5 Claims. (Cl. 101—148)

The present invention relates to lithographic presses, and more particularly to a lithographic press incorporating a moistening roll of novel construction and operating characteristics.

The forms and varieties of inking and moistening devices for lithographic plates are almost without number. In the more usual rotary form of press, these devices are commonly in the form of rolls adapted to bear upon the cylinder supporting the plate. There may be one or more inking rolls, and one or more moistening rolls, these rolls usually being disposed about the plate cylinder in such a way that each portion of the plate passes consecutively over the moistening roll or rolls, over the inking roll or rolls, and over the transfer or blanket cylinder.

Heretofore, it has been commonly believed in the art that only an extremely limited number of copies could be satisfactorily produced by a press of this type without more or less frequent replenishment of the ink and moistening rolls. Consequently, in the larger presses replenishing means are provided to permit continuous operation, while in the smaller presses it is necessary to stop the printing at intervals to sponge the moistening roll and to replenish the ink by hand, unless other means are provided.

Where ink and water replenishing means are incorporated into the press to permit continuous operation, they usually take the form of troughs or fountains, and wicks or rolls adapted to transfer the ink or water to the ink or moistening rolls uniformly, and at a rate conforming with that of ink or water depletion. This apparatus increases the cost, weight, difficulty of maintenance, and bulk of the press, for which reasons it is usually preferable in the smaller or portable sizes to eliminate the replenishment means altogether in favor of manual replenishment at intervals as required. This greatly reduces the speed of the press, and introduces the further complication of periodically upsetting the balance of the ink and water supplies. Ordinarily, an unreplenished moistening roll tends to dry out more rapidly at its ends, while the center portion remains relatively more moist. Thus, since the depletion of the ink on the surface of the ink roll is relatively more uniform, the longer the press is used without replenishment the more non-uniform the ratio of ink to water supply on the surface of the plate becomes. It is therefore seen that when the press is stopped and the water or ink replenished, as by applying a sponge to the moistening roll, the unbalance is further aggravated, since it is extremely unlikely that the ink and water will be replenished in parallel or proportionate quantities.

It is therefore a principal object of the present invention to provide a lithographic press of simple construction, having a single moistening roll and a single inking roll having no external replenishing means, yet capable of printing a much larger number of copies during a continuous period of operation than has heretofore been possible.

Another object is to provide an improved form of moistening

2

tening roll having self-replenishing means capable of rendering the supply of moisture more uniform upon the surface of the roll.

A further object of the invention concerns the overcoming of a disturbing phenomenon which has been found to cause erosion and gradual destruction of metallic lithographic plates. Tests made upon lithographic presses of standard construction have shown that a spurious electrolytic action may develop between the plate and the moistening roll, particularly when the moistening roll is wet with acid. Measurements of as much as 0.8 volt, and currents well in excess of 45 microamperes have been measured. It is therefore an object of this invention to provide a form of moistening roll adapted to the ends heretofore mentioned, and further provided with means to minimize this electrolytic action so as to greatly minimize, if not entirely eliminate, the destructive erosion of the plates.

With the above objects in view, a principal feature of the present invention consists in the use of an improved moistening roll having a rigid cylindrical tube surrounded by a porous fabric cover turned into the tube at the ends, and retaining means for the cover including bushings to support the roll upon a shaft, whereby the roll may be replenished, for example, by sponging its external surface, the water passing around the ends of the cover to the in-turned extremities, where it is available to replenish the outside surface during operation in much the same manner as a wick.

Another feature is the use of an electrically insulating retaining sleeve adapted to secure the fabric cover firmly upon the tube, and to isolate the tube and cover from the shaft.

According to another feature of the invention, the cylindrical tube can be imperforate, and the total amount of water which can be supplied to the roll at any one time is limited by saturation of the fabric cover; yet, the rate of moisture diminution during operation of the press closely parallels the rate of diminution of the ink, whereby an exceedingly large number of copies of high quality may be produced before replenishment is again necessary.

Other features and objects of the invention include certain details of construction, modifications, and arrangements which may be more readily understood in relation to the following description, and which are more particularly defined in the claims.

In the drawings,

Fig. 1 is an end elevation, partially cut away, showing the essential related parts of a lithographic press incorporating a preferred embodiment of the invention;

Fig. 2 is a longitudinal section of a preferred form of the moistening roll; and

Fig. 3 is an illustration showing the preferred manner of shaping the in-turned ends of the roll cover.

Fig. 1 shows the principal working components of a roll-fed, or "web-fed," rotary off-set lithographic press. The severing mechanism for the web is assumed to be in position to cut the web into sheets after printing, but is not shown since it forms no part of the present invention.

The feeding mechanism, including the mechanism for rotating the plate, blanket, and impression cylinders and for feeding the web are of conventional form. The web of paper 2 is fed from a supply roll 4 around a fixed shaft 6 and decurler bar 8 to the "bite" formed by pressure between a blanket or off-set cylinder 10 and an impression roll 12. Preferably, the axis 14 of the blanket roll is fixed in the frame 15 of the press, and the axis 16 of the impression roll is movable vertically to permit control of the bite pressure. The feeding force which draws the web from the roll 4 is supplied solely and

continuously by the bite. The blanket roll preferably consists of a metal support with a rubber sleeve 18 vulcanized to its surface, then turned down to shape in accordance with usual practice in forming printing cylinders and the like. In this form of construction, there are preferably no discontinuities in the surface of the sleeve 18. A plate cylinder 20, preferably of the same diameter as the blanket cylinder, is mounted upon an axis 24 directly above and in line with the axes of the blanket and impression cylinders. A plate 22 is secured to the cylinder 20 by appropriate means, not shown. The axis 24 of the plate cylinder is movable vertically, being supported in a slidible block 26 movable in a slot 28 in the frame 15. Downward force is exerted on the block 26 by a spring 30, and adjustable screw means 32, 34 are provided to adjust the pressure of the plate cylinder upon the blanket cylinder.

The ink roll comprises a hard rubber roll 36 supported on a shaft 38 journaled between end plates 40, each of the end plates having hooks by which to hang the roll over a rod 42 secured to the frame 15. A support rod 44 joins the end plates 40 to give rigidity to the structure, and to support a handle bar 46, which is preferably mounted midway of the roll. The handle 46 is used principally for convenient removal of the roll from the press and re-inking by rolling upon a flat plate upon which printer's ink has been spread. It also provides manual means for adjusting the pressure of the ink roll upon the plate 22, although in normal operation no pressure need be applied to the handle, since the shafts 38 and 42 are off-set from one another, causing the roll 36 to apply a constant, normal component of force to the plate.

The structure of the moistening roll may be seen more readily by reference to Fig. 2. This roll has a rigid cylindrical tube 48, preferably made of stainless steel, and having a continuous imperforate surface. A porous fabric cover 50 surrounds the tube, with its ends being turned into the tube, as shown. The cover 50 may be constructed of any suitable material, but is preferably made of a molleton fabric resembling terry cloth, formed in the shape of a seamless sleeve. Referring to Fig. 3, the in-turned ends of the cover are preferably cut away to reduce the bulk of the fabric inside the tube. It will be noted that, contrary to the usual construction of molleton rolls, the cover is not stitched at the ends.

The cover is held in place by retaining means comprising retaining sleeves 52 and bushings 54. The sleeves 52 are cylindrical in shape, and preferably constructed of Lucite or other electrically insulating material. The sleeves 52 are inserted into each end of the tube 48, preferably meeting in the center when they are fully in position to isolate the cover completely from the shaft to be journaled in the bushings 54. This serves the dual function of preventing electrical conduction from the cover to the shaft, and also preventing the tendency of the in-turned ends of the cover to wrap around the shaft during operation of the press. It will be obvious that non-insulating material may be used for the sleeves 52 if the bushings 54 are constructed of suitable non-conducting material such as nylon.

Water or other moistening agent is applied to the moistening roll by wetting the outside surface of the cover 50, for example with a sponge. When this is done, the water tends to flow around the ends of the cover to the extremities thereof on the inside of the tube 48. The pressure of the retaining sleeves 52 is not so great as to prevent an appreciable quantity of water from thus moistening the inner periphery of the cover. When the printing operation is begun, the moisture on the surface of the cover 50 tends to be depleted more rapidly at the ends than elsewhere, as heretofore described. However, by reason of the moisture in the in-turned ends of the cover, a capillary flow similar to the action of a wick takes place. The moisture flows

out around the ends the tube 48 and replenishes the surface of the roll, starting at the ends where depletion is more rapid, and working toward the center portion.

The results observable with this construction are somewhat surprising. It is expectable that the moistening roll should produce more acceptable copies without replenishing than a roll having no in-turned ends, simply by reason of the increased water capacity. However, the increase in the number of acceptable copies which may be turned out consecutively without replenishment is substantially out of proportion to what might be expected from the increased capacity alone. For example, a press constructed in accordance with this invention has actually produced as many as 1500 highly legible copies from a paper plate without a single replenishment or stoppage of the press for any reason.

In part, these results are attributable to the fact that the replenishing process takes place smoothly and evenly from the ends of the roll. In large measure, however, the results are due to the fact that with this novel construction it is possible to so design the press that the rates of ink and water depletion remain parallel for a considerably longer time than is possible with presses not incorporating automatic and continuous replenishing means. It is apparently this balance of rates of depletion, rather than the absolute quantities of available ink and moisture, which principally determines the legibility of copies. Thus, by using the construction herein described, it has now become possible to adjust the above balance to receive the great benefits which may be derived therefrom. For example, the balance may be effected by using a choice of covering materials, or by changing the relative diameters of the ink and moistening rolls. Different kinds of ink may also affect the balance. In any event, the method is to achieve the necessary balance, and this is more readily achieved with the particular construction of moistening rolls herein described.

It will be understood that many variations of construction, arrangements of parts, and variations of design may be made in the apparatus in accordance with procedures and techniques well known in the art, and without departing from the spirit and scope of the invention.

Having thus described our invention, we claim:

1. A moistening roll for a lithographic press, comprising a rigid imperforate cylindrical tube, a porous fabric cover surrounding the tube, said cover being adapted to permit capillary flow of liquid therethrough and being substantially longer than the tube and having its ends turned inwardly of the ends of the tube and extending into the interior thereof, and sleeves within the in-turned cover portions adjacent the outer ends of the interior of the tube, the cover intermediate the sleeves and the tube being free to transfer moisture between the cover outwardly of the roll and the inturned ends inwardly of the tube.

2. A moistening roll for a lithographic press, comprising a rigid imperforate cylindrical tube, a porous fabric cover surrounding the tube, said cover being adapted to permit capillary flow of liquid therethrough and being substantially longer than the tube and having its ends turned inwardly of the ends of the tube and extending into the interior thereof, sleeves within the inturned cover portions adjacent the outer ends of the interior of the tube, the cover intermediate the sleeves and the tube being free to transfer moisture between the cover outwardly of the roll and the inturned ends inwardly of the tube, and means including said sleeves for supporting the roll upon a shaft, the sleeves being of insulating material to electrically insulate the tube from the shaft.

3. A moistening roll for a lithographic press, comprising a rigid imperforate cylindrical tube, a porous fabric cover surrounding the tube, said cover being adapted to permit capillary flow of liquid therethrough and being substantially longer than the tube and having its ends turned inwardly of the ends of the tube and extending into

the interior thereof, sleeves within the inturned cover portions adjacent the outer ends of the interior of the tube, the cover intermediate the sleeves and the tube being free to transfer moisture between the cover outwardly of the roll and the inturned ends inwardly of the tube, means including said sleeves for supporting the roll upon a shaft, the sleeves being of insulating material to electrically insulate the tube from the shaft, and means for preventing electrical contact of the inturned ends of the cover with the shaft.

4. A moistening roll for a lithographic press, comprising a rigid imperforate cylindrical tube, a porous fabric cover surrounding the tube, said cover being adapted to permit capillary flow of liquid therethrough and being substantially longer than the tube and having its ends turned inwardly of the ends of the tube and extending into the interior thereof, sleeves within the inturned cover portions adjacent the outer ends of the interior of the tube, the cover intermediate the sleeves and the tube being free to transfer moisture between the cover outwardly of the roll and the inturned ends inwardly of the tube, and means including said sleeves for supporting the roll upon a shaft, the sleeves being of insulating material to electrically insulate the tube from the shaft, said sleeves having portions extending inwardly of the tube to maintain the inturned ends of the cover material out of electrical contact with the shaft.

5. A lithographic press having ink-supplying means consisting of a single ink roll adapted to carry on the surface thereof a supply of ink sufficient to permit printing for a substantial period without replenishment and

moisture-supplying means consisting of a single moistening roll adapted to carry a self-contained supply of liquid for operation for a period substantially coextensive with the period of ink supply, the moistening roll comprising an imperforate tube, a porous fabric cover surrounding the tube and having extended end portions turned into and extending a substantial distance inwardly within the tube, roll supporting means within the tube ends inside the inturned cover material, said roll supporting means securing the inturned cover material adjacent the tube ends while permitting moisture transfer to the cover material within the tube when the cover outwardly of the tube is moistened, whereby said moistened inturned ends provide a source of moisture supplementing the moistened outside cover to afford a substantially constant ink/moisture ratio as the ink and moisture are consumed during press operation.
